Victor J. Evans ATTORNEY.

UNITED STATES PATENT OFFICE.

RUDOLPH G. SCHAUER, OF WOODBURY, NEW JERSEY.

FOLDING SEAT.

1,387,315.

Specification of Letters Patent.

Patented Aug. 9, 1921.

Application filed January 23, 1920. Serial No. 353,476.

To all whom it may concern:

Be it known that I, RUDOLPH G. SCHAUER, a citizen of the United States, residing at Woodbury, in the county of Gloucester and 5 State of New Jersey, have invented new and useful Improvements in Folding Seats, of which the following is a specification.

This invention relates to folding seats and it has more particular reference to that type 10 of seat or chair which is made entirely or substantially so of metal, and it has for its main object to provide a seat or chair which can be folded up into a compact space or can be promptly changed from a folded 15 condition to an open one and in which latter position it constitutes a firm and reliable support.

A further object of this invention is to provide a folding seat or chair which is absolutely 20 sanitary in every respect and which when employed or used in public parks or exposed to open air conditions it will rapidly dry should it be rained on or otherwise become covered with moisture or the 25 like.

Still further the invention comprehends the provision of a seat or chair which is simple and cheap to manufacture and which has no parts which are liable to get out of 30 order or become easily damaged.

With these and other objects in view my invention consists essentially in the novel features of construction, combination and arrangement of the various parts hereinafter 35 fully described and more specifically defined by the appended claims.

In the further disclosure of the invention reference is to be had to the accompanying sheet of explanatory drawings constituting a 40 part of this specification and in which like characters of reference designate the same or similar parts in all the views.

Figure —1— is a fragmentary front elevation of a seat or chair embodying my 45 present improvements, parts being broken away or in section to better illustrate the underlying structure.

Fig. —2— is a similar fragmentary side view.

50 Fig. —3— is a plan view.

Fig. —4— is a fragmentary sectional plan taken approximately on the line 4—4 in Fig. 2, and drawn to an enlarged scale for the sake of clearness.

55 Fig. —5— is a fragmentary detail view

to an enlarged scale of one of the seat supporting members and its associated parts.

Referring to the drawings the numeral 10 designates the seat frame proper and it is preferably made of angle section metal with 60 a rounded angle or fillet portion 11, so that no objectionable edge is presented to the user. This frame 10 may be of any desired contour in plan but I have illustrated it as substantially square, and it will be obvious 65 that it may be fashioned from a length of angle metal and have the ends welded; or it may be formed as a stamping in one piece. Adapted to repose snugly on the frame 10 is the seat 12 appropriately consisting of a 70 sheet metal stamping having radial depressions or grooves 13, connecting with a central opening or hole 14 so that rain or the like drains rapidly off the seat when left exposed. It will also be noted that the 75 grooves 13 serve to stiffen or maintain the seat in proper shape and prevent warping. This seat 12 is preferably held in place on the frame 10, by depending turn buttons 15 which firmly grip the underside of the 80 horizontal flange of said frame 10, and formed integral at the rear thereof are hinge members 16 between which is pivoted the back 17, conveniently formed from metal stamping 18, to which is secured a wirework 85 backing 19, and said back is provided at its lower edge with a depending lip or flange 20 which when the seat is in use rests on the rear part of the frame 10 and firmly supports the back 17 in slightly inclined 90 rearwardly disposed position.

The legs or supporting members each include an angle section 21, which is hinged at its upper end to the inner depending flange of the seat frame 10, by strong hinge 95 members 22, appropriately riveted thereto at 23, and the lower ends of the sections 21, are cut at the angle and one or both flanges turned transversely thereto to constitute solid feet 24. The side rails are formed of 100 angle sections 25, and they are rigidly secured to the legs 21 as by rivets or the like 26, and thus it will be seen that each side pair of legs are firmly braced together. The front and rear rails are made of angle sections 27, 28, which are hinged to the legs at 29, 30 respectively and the ends are cut or otherwise formed to abut and overlap at 31, while a pin 32 is provided on the section 28, with which co-operates a bayonet slot 33, 110

on the section 27, whereby the parts are locked in rigid relation when the seat is folded out for use and as will be clearly understood on an examination of the drawings, and it is to be further remarked that the outer ends of the angle sections 27, 28, are cut and turned over at 34 so that said sections are rigidly supported horizontal when folded down in use whereby the legs

10 21 are maintained substantially vertical.

Bracing wires 35 of a more or less flexible nature are threaded through holes 36, in the frame 10, and secured to pins 37 on the legs 21 to aid in securing a more rigid bracing of the entire structure and it will be seen that by their flexible nature they do not interfere in any way with the folding up of the seat when not in use.

From the foregoing description it will be 20 obvious that the folding up of the seat or chair is simply and expeditiously effected by knocking the front and rear rails 27, 28, upwardly whereby the joint is broken between the pin and slot connection 32, 33, 25 whereupon the legs 21, can be folded down snugly within the frame 10. Furthermore the back 17, can be folded down compactly on the seat 12, which results in the seat presenting an exceedingly compact and neat 30 exterior for storage or packing purposes, on the other hand it will be conceded that the setting up of the seat or chair from folded down to a position for use can be very promptly accomplished.

35 Finally it will be readily understood that by my invention I provide a simple, cheap

and very compact and serviceable sanitary seat or chair, and while I have described a preferred construction it will be obvious that slight changes may be made in the 40 shape and form of the several parts without departing from the essential features, such changes and other combinations however being limited by the scope of the appended claims.

45

Having described my invention what I claim as new and desire to secure by Letters Patent is:—

1. A sheet material chair seat having a central opening and also having radial depressed stiffening portions forming channels communicating at their inner ends with said central opening.

2. In a chair, the combination of a rectangular open frame of angle iron, hinges 55 having members fixed to the pendent portions of opposite bars of the frame, and pairs of legs fixed with respect to the other members of the hinges, the legs of each pair being connected together, and being 60 arranged when not in use to be nested in the angle iron frame, with a seat superimposed on the frame and having pendent turn buttons detachably arranged with the horizontal portions of the frame bars, and a 65 back hinged to the seat and having a pendent portion adapted to bear against the frame to maintain the back in working position.

In testimony whereof I affix my signature. 70

RUDOLPH G. SCHaub.
